LATHING MATERIAL

Joseph L. Finek, Brooklyn, N. Y.

Application October 13, 1945, Serial No. 622,119

6 Claims. (Cl. 72—117)

1

The present invention relates generally to lathing material and more particularly to a metal lathing material, such as expanded metal, or the like.

One of the objects of the present invention is to provide a self-furring metal lathing material. Thus the present lathing material when applied against the studs or sheathing on the inside or outside of a frame wall or against a brick wall provides an air space between the lathing material and the wall.

Another object of the present invention is to provide such a self-furring lathing material which will have a substantially monoplanar plaster-receiving front face and which will be substantially free of all obstructions on its plaster-receiving face so that the plasterer may perform the plastering operation with facility.

A still further object of the present invention is to provide a metal lath which also constitutes an insulating building material. For this purpose, the metal lath is backed by a flexible sheath-form insulating material in the form of a building paper coated with aluminum or aluminum foil. The aluminum coated building paper, with the aluminum coat on its rear side, namely, on the side exposed to the wall, serves to reflect radiated heat and prevent the transmission of radiated heat across the air space between the lathing and the wall.

The present invention further aims to provide metal lathing material which is combined with a metal coated building paper so as to convert the lathing into an insulating material, the combination or structure being such as to prevent any of the plaster or any of the liquids in the plaster from gaining access to the aluminum coating on the building paper. Such liquids would corrode the aluminum foil or any other aluminum coating on the building paper. In the present invention, therefore, furring or spacing strips or grips are employed which serve to grip, fix, and firmly attach the metal coated building paper onto the back of the metal lath.

Other objects and advantages of the present invention will be understood by persons skilled in the art from a reading of the following specification and from the accompanying drawing which illustrates the present invention.

In the drawing:

Fig. 1 is a diagrammatic cross section of the lathing material;

Fig. 2 is a cross section of this lathing material mounted on a wall;

2

Fig. 3 is a section taken along the line 3—3 of Fig. 2; and

Fig. 4 is a face view of the lathing material. The present invention aims to provide a building material which comprises within it permanently assembled the desired elements so that the same serves as a plaster lath, and as an insulating building material, and so that when the same is nailed by the customary operation in the building art against the wall and firmly attached to the wall with an air space between the wall and the lath, the lath provides a substantially continuous plaster-receiving face and at the same time this material embodies a heat-reflecting building paper such as a building paper coated with metal such as aluminum or aluminum foil.

Any suitable lathing material may be employed in the construction of the present building material. As illustrated in the accompanying drawing, the expanded metal lath 10 is employed in the present assembly. Such lathing material permits the plaster to enter the openings in the material and thus becomes located with and to the lathing material. In the present invention the back face of the metal lath 10 is lined with the building paper 11 which may be in the form of any suitable asphalt coated paper, or kraft paper, or any other suitable paper. On its back face, namely, on the face that would be exposed to the wall, the building paper 11 is adhesively covered with aluminum foil 12. The paper lying against the back of the metal lath will prevent the extrusion of excessive amounts of plaster through the openings in the metal lath.

In order to maintain the aluminum coated building paper and the metal lath in fixed and permanent assembly, the metal lath is provided with rearwardly extending ribs. These are preferably parallel to each other and extend either lengthwise or widthwise of the metal lath, as desired. It will be noted that these ribs 13 are formed by crimping the metal lath. While these ribs or crimped portions should extend entirely across the dimension of the sheets of metal lath, their depth may be varied.

Essentially the depth of the rib or crimping should be large enough so that it may be gripped by the spacing or furring strip 14. The furring strip 14 may be employed in the form of the spaced short sections. It is preferred, however, that the same be coextensive with the ribs 13 so that thereby it may offer rigid support to that portion of the metal lathing. The aluminum coated building paper is also suitably crimped, as shown, and its crimping overlies the ribs 13.

The furring strips 14 serve to grip and firmly attach the building paper to the metal lath.

The furring strip 14 may be made of sheet metal or impregnated fiber and may be pre-formed to the shape shown. It will be seen that the side walls of the furring strip are provided with their curved portions 15 which face each other and which also provide outwardly flared edges 16.

After the furring strips 14 are assembled over the ribs 13 with the building paper interposed, the assembly is subjected to a further crimping operation with the result that the curved portions of the side walls of the furring strip 14 form a rigid and firm assembly together with the aluminum coated building paper and the ribs 13. The depth of the furring strip 14 may be varied as desired and will depend upon the particular use to which the material is to be put and will depend, of course, upon the size of the air space that may be desired. The bottom of the furring strip 14 is preferably flat so that it will rest solidly against the surface to which it is applied.

In use, the material is placed against the wall 20 with the bottom of the furring strips resting solidly against them and nails 21 are driven through the ribs 13 and the bottoms of the furring strips 14, as shown, and into wall 20. The broad heads 22 of the nails 21 will tend to lodge in the flared portion of the channel and will thus serve to grip the expanded metal and the aluminum coated building paper between its head and the flared portions of the furring strip 14.

It will now be understood that the present material constitutes a unitary product which forms a self-furring and heat insulating lathing material. The metal coated building paper is held against the metal lathing by friction exerted by the furring strips against the ribs. The building paper thus can well withstand the force exerted by the plasterer in applying the plaster on the lath. The paper will not tear and will serve to limit the amount of extruded and wasted plaster. The ribs or ridges 13 add rigidity to the metal lath and generally improve the rigidity of the finished plaster wall. It will also be appreciated that the present building material may be installed without any operations other than those customarily employed in the installation of metal lath in that the only operations that need to be performed on the building job is driving the nails 21 through the metal and onto the wall.

I claim:

1. An insulating building material comprising in combination, a metal lathing material having a plaster receiving front face and a rear face, the material having on its rear face spaced parallel ribs, a layer of paper on its rear face, the paper bearing a coating of heat reflecting material on its rear face, spacing and gripping strips disposed over said ribs serving to hold the paper in assembly with the metal lath, said strips being substantially channel shaped and serving to re-

ceive nails for mounting the lathing on the wall and to space the lathing from the wall.

2. A self-furring lathing comprising in combination, a metal lathing material having a plaster receiving front face and a rear face, the material having integrally formed ribs on its rear face, a layer of paper on its rear face, the paper bearing a coating of aluminum on its rear face, gripping means disposed over said ribs serving to hold the paper in assembly with the metal lath to receive nails for mounting the lathing on the wall and to space the lathing from the wall.

3. An insulating building material comprising in combination, a metal lathing material having a plaster receiving front face and a rear face, the material having integrally formed ribs on its rear face, a layer of paper on its rear face, the paper bearing a coating of aluminum on its rear face, gripping strips disposed over said ribs serving to hold the paper in assembly with the metal lath, said gripping strips being substantially channel shaped and serving to receive nails for mounting the lathing on the wall and to space the lathing from the wall.

4. An insulating building material comprising in combination, a metal lathing material having a substantially monoplanar plaster receiving front face and a rear face, the material having integrally formed ribs on its rear face, a layer of paper on its rear face, the paper bearing a coating of aluminum on its rear face, gripping strips disposed over said ribs serving to hold the paper in assembly with the metal lath, said gripping strips being substantially channel shaped and having outwardly flared free edges, the strips serving to receive nails for mounting the lathing on the wall and to permit the head of the nail to lodge in the flared portion of the strip.

5. A self-furring lathing comprising in combination, a metal lathing material having a plaster receiving front face and a rear face, the material having integrally formed ribs on its rear face, a layer of paper on its rear face, and spacing strips disposed over and gripping said ribs, said strips being substantially channel shaped and serving to receive nails for mounting the lathing on the wall and to space the lathing from the wall, said strips also serving to hold the paper in assembly with the metal lath.

6. A self-furring lathing comprising in combination, a metal lathing material having a plaster receiving front face and a rear face, the material having parallel reentrant strips forming ribs on its rear face, a layer of paper on its rear face, and spacers disposed over and gripping said ribs, said spacers being substantially channel shaped, and having outwardly flared free edges, the spacers serving to receive nails for mounting the lathing on the wall, said spacers also serving to hold the paper in assembly with the metal lath.

JOSEPH L. FINCK.
